(57) CLAIM

The ornamental design for a toilet bowl for obese persons, as illustrated and described.

DESCRIPTION

FIG. 1 is a perspective view of a toilet bowl for obese persons;

FIG. 2 is a front side view of the embodiment shown in FIG. 1;

FIG. 3 is a left side view of the embodiment shown in FIGS. 1-2;

FIG. 4 is a back side view of the embodiment shown in FIGS. 1-3; and,

FIG. 5 is a top view of the embodiment shown in FIGS. 1-4. The broken line showing of various features of the toilet bowl is for illustrative purposes only and forms no part of the claimed design.
